DESIGN FOR A TOP UNIT FOR OIL COOKING STOVES

Harold H. Niemann, Wisconsin Rapids, Wis., as
signor to Prentiss Wabers Products Co., Wisconsin
Rapids, Wis., a corporation of Wisconsin

Application August 10, 1945, Serial No. 121,372

Term of patent 7 years

(Cl. D81—25)

To all whom it may concern:

Be it known that I, Harold H. Niemann, a citizen of the United States, residing at Wisconsin Rapids, in the county of Wood and State of Wisconsin, have invented a new, original, and ornamental Design for a Top Unit for Oil Cooking Stoves, of which the following is a specification, reference being had to the accompanying drawing, forming a part thereof.

Figure 1 is a plan view of a top unit for oil cooking stoves embodying my new design.

Fig. 2 is an edge elevational view of the same.

Fig. 3 is a fragmentary sectional view taken approximately in the plane of line 3—3 of Fig. 1 and on an enlarged scale.

Fig. 4 is a fragmentary sectional view taken approximately in the plane of line 4—4 of Fig. 1, also on an enlarged scale.

I claim:

The ornamental design for a top unit for oil cooking stoves, substantially as shown.

HAROLD H. NIEMANN.
